PADLOCK

Samuel R. Fraim, Lancaster, Pa.

Application September 26, 1934, Serial No. 745,626

10 Claims.

(Cl. 70—108)

My invention relates to certain improvements in padlocks of the type having a sliding shackle engaged by a locking spring located in a housing, the spring being operated by a key-controlled tumbler mechanism.

One object of my invention is to so design a lock of the type above mentioned that it can be manufactured at a reasonable price without impairing its efficiency.

Another object of the invention is to so design the spring housing and the tumbler insert that they can be readily assembled and inserted in the lock casing between the posts of the lock.

A still further object is to provide a bridge in which the disc tumbler plug is mounted so as to allow the plug to freely turn, the bridge holding the plug in position in the casing in respect to the spring housing.

The invention also relates to certain details of construction which will be described hereinafter.

In the accompanying drawing:

Fig. 1 is an interior view of my improved padlock, the front plate of the casing being removed;

Fig. 2 is a sectional elevation on the line 2—2 of Fig. 3;

Fig. 3 is a transverse section on the line 3—3, Fig. 1;

Fig. 4 is a sectional plan view through the casing and the spring housing on the line 4—4, Fig. 1;

Fig. 5 is a sectional plan view on the line 5—5 Fig. 1;

Fig. 6 is a detached perspective view of the back plate of the casing showing the posts attached;

Fig. 7 is a detached perspective view of the front plate of the casing;

Fig. 8 is a detached perspective view of the shackle;

Figs. 9 and 10 are perspective views of the locking spring housing;

Fig. 11 is a detached perspective view of the locking spring;

Fig. 12 is a detached perspective view of the bridge piece in which the disc tumbler plug is mounted;

Fig. 13 is a detached perspective view of the disc tumbler plug;

Fig. 14 is a detached view of the ejecting spring;

Fig. 15 is a detached view of the plate for centering the ejecting spring on the bottom of the casing;

Fig. 16 is a view similar to Figure 1 showing a

pin tumbler assembly in place of a disc tumbler plug and also means for holding the pin tumbler assembly in position;

Fig. 17 is a detached perspective view of the pin tumbler assembly shown in Fig. 16;

Fig. 18 is a perspective view of the retaining plate for the pin tumbler assembly; and

Figs. 19 and 20 are views illustrating modification of the pin tumbler assembly.

Referring to the drawing—I is the casing of the lock made in two sections as shown in Figs. 6 and 7; 2 is the flanged bottom plate from which extend the posts 3—3a, and 4 is the flanged top plate having holes therein to receive the posts, the ends of which are riveted over the top plate after the mechanism of the lock has been assembled on the bottom plate and the top plate is placed in position. The flanges of both the top and bottom plates are notched to receive the tumbler plug and the shackle.

The shackle 5 is of the ordinary sliding and swinging type and has a long leg 6 and a short leg 7. The long leg in the present instance is notched at 8—8 on both sides to receive the two arms 9—9 of the locking spring 10 shown in Fig. 11. This locking spring 10 is located in a spring housing 11, shown in Figs. 9 and 10 and when the arms of the spring engage the shackle, it is locked in the closed position. When a key is inserted in the cylinder plug of a locking assembly and turned, the projection 19 of the plug 20 that extends into the housing 11 and between the arms 9—9 of the locking spring 10 will spread the spring arms apart and release the shackle which will be projected by the ejecting spring 12 which is located between the end of the long leg of the shackle and bottom of the casing of Fig. 1. In the present instance, the spring is held in position on the bottom of the casing by a notched plate 13, Fig. 15. On the long leg of the shackle is a lug 14 which limits the outward movement of the shackle, when the shackle is projected the lug will strike the locking spring housing 11.

The transverse locking spring housing 11 is made of sheet steel bent in U-shaped form providing upper and lower plates 15 and 16 and a connecting member 17 and extends from side to side of the casing. The upper and lower plates of the housing are perforated at 11a—11a for the passage of the long leg of the shackle, and the lower plate 16 is slotted at 18 for the rectangular projection 19 on the inner end of the tumbler plug 20. The side walls of the slot 18 incline from each end towards the center so that the slot is narrow at the center and enlarged at each end,

this construction allows the plug projection 19 to turn in the slot to spread the arms of the locking spring but the walls of the slot limit the turning movement of the projection. The movement is sufficient to release the shackle.

The tumbler plug 20 has a series of disc tumblers 21 therein and has a key slot 22 which extends through the tumbler discs so that when a proper key is inserted in the plug slide the discs 10 release the plug from the bridge piece 23.

The bridge piece is U-shaped in form having a flat top member 24 and slotted side members 25-25, the slots 26 in the side members allowing the disc tumblers to be moved therein to lock 15 the plug 20 to the bridge piece and as the bridge piece fits between the front and back plates of the housing, it is held rigidly in position.

The plug 20 has a flange 27 at its outer end which bears against the inner wall of the casing 20 and this flange has a reduced projection 28 which extends through the hole in the bottom of the casing. The bridge piece is fitted between the inner surface of the flange 27 on the plug and the spring housing as shown in Figs. 1, 2 and 3 and as 25 the housing rests against the two upper posts and fits between the side walls of the casing, both the spring housing and the bridge piece with the plug are held firmly in position. The bridge piece also fits between the two lower posts 3a-3a. The 30 side walls of the bridge piece 23 are shaped to conform to the plug as shown in Fig. 12. It will be noticed in referring to Fig. 5 that the angles formed on the edges 29 of the slots 26 hug the plug 20 very closely and, as the inner sides of the 35 edges are sharp, they preclude any possibility of the wafers or discs carried by the plug being forced past these edges by a key whose bittings do not correspond to the respective discs or wafers which are designed specifically to the depth of 40 key biting. This prevents the opening of the lock by a key whose bittings are not in conformity to the actual arrangement of the individual wafers. I have not illustrated the tumblers in detail as 45 they are of the standard type.

The locking spring 10 has a loop 9a in the present instance at one end from which extends the two arms 9-9, Fig. 11. The springs are spaced apart by the projection 19 on the plug 20 and are bent towards each other at their ends to insure their engagement with the notched portions 8-8 of the shackle. When the plug is turned by a key the projection 19 spreads the arms 9-9 of the spring apart and releases the shackle allowing it to be projected by the ejecting spring. The arms 50 are held apart by the shackle until it is closed 55 when the arms of the spring snap into the notches, locking the shackle to the casing. The looped end 9a of the spring is held between bottom plate of the casing and a curved tongue 34 and a short tongue 35 projecting from the housing 11, see Fig. 4.

In Figs. 16, 17 and 18, a modification is shown in which pin tumblers are used in place of disc tumblers. In this instance, cylinder 23a is substituted for the bridge piece. This cylinder has a side extension 30 for the sliding pins, not shown as this cylinder is of standard type. In order to prevent the cylinder turning in the casing, an angle-shaped plate 31 is inserted at the corner 70 of the lock casing and fits between a post 3b and the side of the casing and between the spring housing and the bottom of the casing, and a notch 37 is formed in the turned up portion of the plate which engages the side extension and prevents the cylinder 32a turning in the casing.

In Fig. 19 is shown a modification of the cylinder. In this instance the side extension 30b is the full width of the cylinder 23b and fits between the top plate and bottom plate of the casing.

In Fig. 20 the side extension 30c of the cylinder 5 23c has lugs 33 at each side which extend to the plates of the casing. In both of these modifications, the angle plate is dispensed with as the cylinder is held from turning by the plates of the casing. 10

While I have described the locking spring as being U-shaped and having two arms, it will be understood that I do not wish to limit myself to the form of locking spring nor do I wish to limit the exact method of securing or holding the locking 15 spring in the housing, as any form of locking spring may be used which will fit the housing and which can be held by any suitable means so long as the spring can be operated by the projection on the plug to release the shackle from engagement by the spring. 20

By the construction described above, the mechanisms of the lock can be readily assembled, after which they can be mounted on the bottom plate 25 of the casing and the top plate secured in position.

I claim:

1. The combination in a padlock of a two-part casing; upper and lower posts connecting the two parts of the casing; a shackle mounted in the casing; a locking spring housing extending from side to side of the casing and resting against the upper posts, said housing having holes for the passage of the shackle and having a slot in its lower plate; a locking spring in the housing engaging the shackle; a locking assembly including a key plug located in the casing between the housing and the bottom of the casing and between the lower posts, a flange on the key plug forming part of the locking assembly said flange having a reduced portion extending through the bottom of the casing, said key plug having a projection extending through the spring housing and engaging the locking spring. 35

2. The combination in a padlock of a two-part casing; upper and lower posts connecting the two parts of the casing; a shackle mounted in the casing; a locking spring housing extending from side to side of the casing and resting against the upper posts, said housing having holes for the passage of the shackle and having a slot in its lower plate; a locking spring in the housing engaging the shackle; a locking assembly including a key plug located in the casing between the housing and the bottom of the casing and between the lower posts, a flange on the key plug forming part of the locking assembly having a reduced portion extending through the bottom of the casing, said plug having a projection extending through the spring housing and engaging the locking spring; a bridge piece enclosing the key plug and forming part of the locking assembly and extending between the flange of the key plug and the underside of the housing, the side walls of the bridge piece having openings therein for discs of the plug, the bridge piece acting as a shell for the key plug and also acting to hold the several parts together. 50

3. The combination in a padlock of a casing, a notched shackle therein, a transverse locking spring housing having holes for the passage of the notched portion of the shackle, a U-shaped locking spring mounted in the housing, the arms of the spring extending to the shackle and arranged to engage the notched portion of the shackle; the lower plate of the housing having a 55 60 65 70 75 80 85 90 95

slot therein; a cylinder plug having a key-way at one end and an elongated projection at the opposite end, said projection extending through the slot in the housing and between the arms of the locking spring, the plug having a flange bearing against the bottom of the casing and having a portion extending through the bottom; and a bridge piece enclosing the plug and located between the flange of the plug and the spring housing said bridge piece acting to hold the parts together.

4. The combination in a padlock of a casing; a notched shackle located in the casing, a transverse locking spring housing having upper and lower plates and a connecting member, said housing having holes for the passage of the notched portion of the shackle, and a slot for the passage of an operating extension of a plug, a locking spring having arms and located in the housing; a flanged cylinder plug having a keyway at one end and a projection at the other end, the projection extending through the slot in the spring housing and between the arms of the locking spring; the housing having a curved tongue engaging the loop of the locking spring and means between the flange of the plug and the spring housing for holding the parts in the casing and forming a bearing for the plug.

5. The combination in a padlock, of a casing, a shackle, said shackle having a long leg and a short leg, this shackle having a notch arranged to be engaged by a locking spring, a transverse spring housing, a locking spring therein, a locking assembly mounted in the casing between the transverse housing and the bottom of the casing, an ejecting spring between the bottom of the casing and the end of the long arm of the shackle, and a notched plate mounted in the bottom of the casing between the side of the casing and the locking assembly and encircling the ejected spring to hold said spring in position.

6. The combination in a padlock, of a casing, a shackle therein having a long and short arm, an ejecting spring for the shackle, the long leg of the shackle having a notch therein, a transverse locking spring housing, a U-shaped locking spring mounted in the housing and having an enlarged circular end, the housing having a segmental tongue partly encircling the end of the spring and having a short tongue to hold the spring in proper engagement in the casing, a cylinder plug mounted in a casing between the housing and the bottom of the casing, said plug having a key-way at one end and a projection at the opposite end extending into the housing and engaging the arms of the locking spring so that on turning the plug by a key, the arms will be spread apart to release the shackle from the spring, the ejecting spring ejecting the shackle so that the short arm of the shackle will clear the housing.

7. The combination of a casing, a shackle mounted in the casing, a transverse spring housing located in the casing, a locking spring mounted in the housing and arranged to engage the shackle, a cylinder plug mounted between the locking spring housing and the bottom of the casing and having a key-way therein, the said plug having a projection extending into the housing and engaging the locking spring; a cylinder surrounding the plug and having a lateral extension; and a plate, having a long arm held against the side of the casing and a short arm bent at an angle with respect to the long arm and having a notch therein into which the projection of the cylinder extends.

8. The combination in a padlock, of a casing; a shackle; a housing; locking mechanism within the housing; a key operated cylinder plug for actuating the locking mechanism; sliding discs in the plug arranged to be engaged by a key inserted in the plug; a bridge piece enclosing the plug and having side openings therein to allow movement of the discs; one edge of each opening fitting the plug closely to prevent the turning of the plug until the discs are entirely withdrawn by the insertion of a key having the proper bitting.

9. The combination in a padlock or a two-part casing; a shackle; upper posts connecting the two-parts of the casing; a transversely arranged locking spring housing resting against said posts, a locking spring located in the housing; said housing having holes for the passage of one leg of the shackle which is engaged by the locking spring; a locking assembly fitting between the bottom of the casing and the spring housing and holding the spring housing against the posts; the locking assembly having a key plug provided with a projection extending into the housing and engaging the locking spring, so that when a key is inserted in the key plug and the plug turned, the arms of the locking spring will be spread apart releasing the shackle.

10. The combination of a casing; a notched shackle; a locking spring housing extending from one side of the casing to the other side, means on the casing against which the housing rests; a locking spring located in the housing and arranged to engage the shackle; the lower plate of the housing having an opening therein; a locking assembly located between the lower plate of the housing and the bottom of the casing, and holding the housing in position, the locking assembly having a key plug therein provided with a key hole in one end and a projection at the other end, said projection extending through the opening in the spring housing and engaging the locking spring.

SAMUEL R. FRAIM.
